N-W EQUIPMENT CO., INC., OF NEW YORK, N. Y., A CORPORATION OF NEW YORK.

FUSE.

1,124,194.

Specification of Letters Patent.

Patented Jan. 5, 1915.

Application filed March 11, 1913. Serial No. 753,584.

To all whom it may concern:

Be it known that I, WILLIAM C. BANKS, a citizen of the United States, residing in the borough of Bronx, city and State of New York, have invented certain new and useful 5 Improvements in Fuses, of which the following is a specification.

This invention relates to fuses of the type commonly employed in electric circuits for 10 opening such circuits when the current flowing therein exceeds a predetermined maximum.

The invention has reference particularly to fuses of this character in which the fusible strip is suitably inclosed and is so held that a disrupted strip may be readily removed and a new one inserted in its place.

The invention is directed particularly to the means whereby the ends of such a 20 renewable fusible strip are gripped and held.

In fuses of this character, it is important that the ends of the fusible strip be gripped very tightly so that the strip will be held in the proper position and good electrical 25 contact shall be made therewith and so that the danger of the connections to the strip working loose under vibration shall be entirely eliminated. Such fuses are used to a large extent on railway rolling stock where 30 they are subjected to severe and continued vibration and with the types of fuses heretofore employed it has frequently happened that the connections to the fusible strip have worked loose.

35 The avoidance of this objectionable characteristic is one of the objects of this invention.

A further object of the invention is to provide means for holding the ends of the 40 fusible strip in such manner that, while the ends are gripped and tightly held when the fuse is in use, it is possible to readily remove the fusible strip or the parts thereof in order to insert a new one.

45 The invention involves the employment of gripping members lying on opposite sides of the fuse and movable in the direction of the length of the fuse, the arrangement being such that when these gripping members 50 are so moved in the direction of the length of the strip, they are caused to move toward each other thereby gripping the fuse tightly so as to hold it firmly in position and make good electrical connection thereto. This 55 movement of the gripping members is ef-

fected by the provision of inclined surfaces on certain of the parts whereby a wedging action takes place. Preferably the inclined surfaces are provided upon the exterior surfaces of the gripping members and these inclined surfaces coact with the inclosing tube 60 of the fuse.

I have illustrated the preferred embodiment of my invention in the accompanying drawings, in which—

65 Figure 1 is a longitudinal section of a fuse constructed in accordance with my invention, Fig. 2 is a view similar to Fig. 1, the plane of the section being at a right angle to that of Fig. 1, Fig. 3 is a view similar to Fig. 1 with the several parts of the fuse 70 slightly separated, Fig. 4 is an end view of the fuse and Fig. 5 is a transverse section at the center of the fuse.

75 Referring to these drawings, the fuse consists of a strip 6 of suitable metallic composition, this strip being contracted at the center thereof in the usual manner. The strip 6 is placed within an inclosing tube 7 made of fiber or other suitable insulating and non- 80 inflammable material.

85 In order to hold the ends of the fuse 6 rigidly in position and to make electrical connection therewith, I provide a pair of gripping members 8 at each end of the tube 85 7, these gripping members being located one on either side of the strip 6. These gripping members are semi-circular pieces as shown in Figs. 4 and 5 and their outer curved surfaces are inclined or tapered as 90 shown in Figs. 1, 2 and 3. The two gripping members are of such size that when in position with the fuse 6 between them their ends project a short distance within the end of tube 7. It will thus be seen that if the 95 gripping members be moved in the direction of the length of the fuse 6 and tube 7, they will be moved toward each other by a wedging action due to the coaction of the inclined surfaces of the gripping members with the 100 interior wall of tube 7. Such movement of the gripping members in the direction of the length of the fuse is effected by a cap 9 which is interiorly threaded and adapted to engage threads on the exterior of tube 7. 105 The end of the cap 9 is partially closed as shown at 10.

110 When the cap 9 is screwed up on tube 7, the flange 10 engages the members 8 and forces them more or less into the tube 7.

When the gripping members 8 are moved thus, they are forced toward each other by a wedging action so that they grip the fuse 6 tightly between them. The fuse is thus held firmly in position and good electrical connection is made between the members 8 and fuse 6 because of the pressure of the members upon the fuse. Also good electrical connection is made between the cap 9 and the members 8, as the cap is screwed up upon tube 7 until it is in hard engagement with the members 8. When the parts have been positioned thus there is no danger of their working loose, as for instance, under the vibration of a moving railway car, as the wedging of the several parts one on another effectually prevents such loosening of the parts.

A further advantage incident to the construction herein shown and described, is that the ends of the fuse 6 may be allowed to project slightly through the openings in the caps 9 and these ends may be stamped with indices of the size or capacity of the fuse.

A further advantage characteristic of the construction herein shown and described is that a passageway is provided from the interior of the fuse to the exterior for the escape of gases and for the relief of high pressure conditions existing within the fuse. It will be noted that the opening in the end of the cap or ferrule is of larger diameter than the width of the end of the fuse, and that spaces are provided between the gripping members beyond the edges of the fuse. Therefore, gases formed within the fuse may escape through the openings between the gripping members at opposite edges of the fuse and thence through the opening in the ferrule or cap.

It will be understood that the construction herein illustrated and described may be modified in certain respects, such, for instance, as the location of the inclined surfaces which cause the wedging action, without departing from the spirit of my invention, and all such obvious modifications I consider within the scope of the invention and I aim to include them within the terms of the claims appended hereto.

Having now described my invention, what I claim as new therein and desire to secure by Letters Patent is as follows:

55. 1. The combination of a fuse, an inclosure therefor made of insulating material, a pair of gripping members lying on opposite sides of the fuse, a cap engaging the inclosure and gripping members and movable relative to the inclosure to cause movement of said members in the direction of the length of the fuse, and means for causing

the gripping members, when so moved by the cap, to move toward each other and grip the fuse between them, substantially as set forth.

2. The combination of a fuse, a tube of insulating material inclosing the same, a pair of gripping members lying on opposite sides of the fuse at one end of the tube and having inclined outer surfaces whose greatest diameter exceeds the interior diameter of the tube, and a cap threaded upon the end of the tube and adapted when turned upon the tube to engage said members and move them in the direction of the length of the fuse, substantially as set forth.

3. The combination of a fuse, a tube of insulating material inclosing the same, gripping members on opposite sides of the fuse at the ends of the tube having inclined exterior surfaces whose greatest diameter exceeds the interior diameter of the adjacent ends of the tube, and caps threaded upon the tube and engaging the gripping members, substantially as set forth.

4. A fuse cartridge comprising a tubular body of insulating material having the inner surfaces of the opposite ends thereof flared outwardly, a pair of wedge blocks disposed within each flared end of said body and having the maximum diameter thereof greater than the minimum diameter of the respective flared end of said body, the confronting faces of the blocks of each pair being flat and designed to receive the ends of the fusible element, and caps closing the ends of said body and adapted for movement upon the body and having the end walls thereof abutting said pairs of wedge blocks whereby the latter will be forced inwardly of the flared ends of the body as the caps are moved toward each other to produce a clamping action.

5. In a safety fuse, a non-conducting casing, terminal caps closing and adjustably mounted on the ends of the casing, sectional inwardly tapering plug members having their larger ends of greater diameter than the internal diameter of the ends of the casing mounted in the ends of the casing with the outer and larger ends in engagement with the caps whereby they are confined in the casing by the caps, and a fuse member having its ends located between the sections of the plugs and clamped thereby when the plugs are forced inwardly by the caps closing the ends of the casing.

This specification signed and witnessed this 6th day of March, 1913.

WM. C. BANKS.
